NECKTIE AND COLLAR CLASP

Jay Hershey Longenecker, Richmond, Va.

Application October 3, 1944, Serial No. 556,946

6 Claims.

(Cl. 24—81)

My invention relates to necktie and collar clasps; and particularly to clasps to be used with four-in-hand, bow, and similar ties. These forms of tie are usually made with a strap or long narrow part which is passed around the neck under the collar, and which engages the bow of the tie to hold it in place. A certain degree of tautness must be put upon the strap; for if the strap is loose the bow will fall from its proper place, and give an untidy look to the dress. A tight strap makes the collar bind about the neck, and is a cause of great discomfort to the wearer; particularly in hot climates, where, unfortunately for them, men in certain professions and businesses are expected to wear the formal shirt and tie. My object is to provide a four-in-hand tie or a bow tie which may be held in place by means of a collar clasp, and without the use of any strap around the neck. Another object is to provide a collar clasp which may be attached to the tie, and which may be opened by the wearer at its ends so that the wing of the collar may be easily passed between the two bars of the clasp, which bars may then be closed upon the collar wing to hold it firmly in place. In well known forms of collar clasps the wing of the collar is pushed between the bars of the clasp. But where it is easy for a collar to be pushed between the bars, it is equally easy for the collar to slip out of their grip. When the spring in the bars is made strong enough to hold the collar, it is a difficult matter to slip the collar between them, and it is often defaced in the process. A particular object of my invention is to provide a clasp which shall firmly hold the wings of the collar; which may be easily opened to introduce the said wings; which may be held open for the adjustment of the collar; and which may then be closed.

In the drawing, which forms a part of this specification: Figure 1 is a partial front view of a collar, with tie and clasp in place; Figure 2 is a rear view of the tie with clasp attached to it; Figure 3 is an enlarged view of the keyed clasp in plan and partly in section, taken on line *a—b* in Figure 4, with one side open and the other side closed; Figure 4 is an enlarged rear view of the keyed clasp in elevation; Figure 5 is a modified form of the clasp shown in Figure 3; Figure 6 is a rear elevation, enlarged, of the clasp without key, enlarged, and Figure 7 is a broken view in elevation of a detached key for use with the clasp shown in Figure 6. Figure 8 is a greatly enlarged view of the cross-section of the actuating part 32 of the key (Figs. 3 and 5) taken substantially on line *a—b* in Figure 4. Figure 9

shows an alternate cross-section 32'; and Figure 10 shows still another alternate cross-section 32".

In Figure 1, the numerals 2, 2 indicate the two wings of a collar. The numeral 4 indicates the bow of a four-in-hand tie; 6 is the flowing part of the tie; and 8, 8 are two tabs attached to the bow 4 of the tie to help to hold it in place under the wings 2 of the collar.

In Figure 2 we see the rear view of the same tie; and adjacent the lower part of the bow 4 is attached, by sewing through holes 5, or by other means, my clasp, designated generally by the numeral 10.

Figures 3 to 7 inclusive are views of my clasp 15 greatly enlarged so that the parts may be clearly seen.

In Figure 3: the front bar 12 of the clasp may be ornamental in design. In it two arced cups 14 and 16 are formed. The ends 18 and 20 of the bar 12 are shown with scrolls for ornamental purposes. Attached to bar 12, and adjacent its center, is the spring-bar 22; held to bar 12 by suitable means, such as the rivet 24.

At 26 and 28 adjacent its ends the spring-bar 25 22 presses strongly against the opposite parts of bar 12 to hold the wings of a collar. The spring-bar 22 is so formed that when its ends are closed against the ends of bar 12 there shall remain a 30 space 30 between bar 12 and spring-bar 22, and intermediate their ends and centers. The purpose of this space is to freely accommodate the collar wing so that it may take a neat set; and so that pressure on the wing at this point shall not hold the end grips of the bars 12 and 22 apart.

In Figures 3 and 5 the end 26 of spring-bar 22 is pressing against the end 18 of bar 12. At the other end of the clasp the end 20 of bar 12 and the end 28 of spring-bar 22 are held apart for the introduction or release of a collar wing. These bar ends, 20 and 28, are being held apart by the key 34, which has been turned in the cup 16. The key may be turned to the position shown in Figure 5, when it may be released, and will still hold the clasp open.

Referring to Figures 3 and 5: the keys 32 and 34 are shown in place. The keys are cylindrical in form, except at that part which lies between the two bars 12 and 22 of the clasp. Each key is about $\frac{1}{6}$ of an inch in diameter; has a finger plate 36; and has two collars 38 and 40 to hold it against displacement from between the bars 12 and 22. That part of the key which lies between the bar 12 and spring-bar 22 is, in cross section, in the form of a segment of a circle greater than a semi-circle; this segment having a flattened

base, as at 42 in Figures 3 and 5, and also in the more greatly enlarged section shown in Figure 8. I prefer this form as it permits the use of a seat of regular outline, as at 14 and 16, to hold the key in place; and as a seat of this regular outline is less expensive than others to form. In Figure 9 I show the key cross-section formed with a slightly curved base; and in Figure 10 I show the key with a still more curved base, so that the cross-section approaches that of an ellipse. I do not confine myself to any one of these particular cross-sections; for any one of them will operate to separate the two bars of the clasp when it, the key, is turned through a considerable angle in its seat; the essential feature of the cross-section used being that one dimension passing through its center shall be shorter than another intersecting it. To express this essential feature briefly, and having explained the form and the function of the key, I shall hereinafter refer to its cross section as cam-shaped, which it approximates in either of the forms shown, and in the sense that the length of the axis in one direction is greater than the length of the axis intersecting the first axis. In other words: extreme dimensions in all directions through the center of rotation are not equal.

In Figure 3 the flat side 42 of the key 32 lies against the spring-bar 22; the end 26 of which is pressing against end portion 18 of bar 12; while key 34 had been turned sufficiently to force end portion 28 of the spring-bar 22 away from end portion 20 of the bar 12. These ends of either bar may be roughened or ribbed, as indicated at 21. But this is not necessary when spring-bar 22 has strength; nor is it desirable with some shirt-collar fabrics.

When the wearer puts on his tie, he places its bow 4 and tabs 8, 8 under the wings of this collar; and with finger and thumb of one hand opens one end of the clasp by turning the key associated with that end. He then adjusts one wing of his collar in the open end of the clasp; turns the key again to close the clasp again upon the said wing. Then he opens the other end of the clasp by turning the key on that side of the center of the clasp; inserts the other wing of the collar; then turns the key to close the ends of the clasp upon this wing. Further adjustment is easily made by holding either key in the fingers of one hand; then adjusting the wing of the collar by the fingers of the other hand. The keys 32 and 34 lie behind the flowing part of the tie.

In Figure 6 the clasp is made as in Figures 3 and 5; but the key is removable from the bar, as shown in Figure 7. This key 47 (shown at about twice its real size) may be made for attachment to a keyring by the ring 48. The cylindrical end is flattened at 49. The end of the key is tapered to make it easy to insert it into the cup of the clasp; for it must be remembered than when in use it is under the tie. The lower collar 40 is retained, to act as a stop against the lower edge 50 of the clasp 10.

The difference between the clasp shown in Figures 3 and 5 and the clasp shown in Figure 6 is that with the latter the key is separate, and with the former the key is held in place in the clasp by the collar 38.

I claim:

1. In combination with a necktie: means for supporting the tie upon the wings of a collar; the

said means comprising a front bar secured to the back of the tie; a spring-bar secured centrally to the back of the front bar, its end portions sprung against the front bar, and each end portion adapted to grip a collar wing against the said front bar; and key means having a cam-shaped cross-section located between the front bar and the spring-bar adjacent the center thereof, and adapted when turned to spring the ends of the spring-bar 10 away from the front bar to allow a collar wing to pass between them.

2. In combination with a necktie: means for supporting the tie upon the wings of a collar; the said means comprising a front bar secured to the back of the tie; a spring bar secured centrally to the back of the front bar, its end portions sprung against the front bar, and each end portion adapted to grip a collar wing against the said front bar; the said front bar and spring-bar 15 being spaced apart between the gripping ends of the spring-bar and the center of the bar to encompass the fabric of the wing; and key means of cam-shaped cross-section located between the front bar and the spring-bar adjacent the center thereof, and adapted when turned to spring the ends of the spring-bar away from the front bar to allow the passage of fabric of a collar wing.

3. A collar clasp comprising a front bar; a rear bar of spring material, centrally secured to the front bar, and having its ends sprung against the front bar; and a key seat formed between the two bars on each side of the center thereof; in combination with a key of cam-shaped cross-section adapted to be inserted in a key seat and turned 30 to press the end of the spring-bar away from the associated end of the front bar.

4. In combination with a necktie: means for supporting the tie upon the wings of a collar, the said means comprising a front bar secured to the back of the necktie; a spring-bar secured centrally to the back of the front bar and adapted to press adjacent each end against the adjacent end of the front bar; a key of cam-shaped cross-section 40 mounted between the front bar and the spring-bar on each side of their common center, and adapted when turned to press against the two bars to open their gripping ends to pass the wing of a collar, and adapted when turned back to its first position to release the gripping ends 45 of the bars to seize the said wing of the collar.

5. A collar clasp comprising a front bar; a rear bar of spring material; the said bars being centrally secured together, and the rear bar adjacent its ends being sprung against the opposite parts of the front bar; key seats formed between the two bars one on each side of the center of their length; and a key of cam-shaped cross-section seated in each key seat and adapted when turned to press the gripping parts of the two bars 55 adjacent their ends apart.

6. A collar clasp comprising a front bar; a rear bar of spring material; the said bars being centrally secured together; and the end portions of the rear bar sprung against the adjacent end portions of the front bar; a key seat formed in one of the two bars on each side of the center of its length; and a key of cam-shaped cross-section seated in the key seat and adapted to be turned therein.
